[57] CLAIM

The ornamental design for a computer generated image for a display panel or screen, as shown and described.

DESCRIPTION

FIG. 1 is a front view of a computer generated image for a display panel or screen showing my new design;
FIG. 2 is a front view of a second embodiment thereof;
FIG. 3 is a front view of a third embodiment;
FIG. 4 is a front view of a fourth embodiment;
FIG. 5 is a front view of a fifth embodiment; and,
FIG. 6 is a front view of a sixth embodiment.

The broken line drawings of a display panel or screen, portions of the image, and the time in all views is for illustrative purposes only and forms no part of the claimed design.

1 Claim, 6 Drawing Sheets
